UNITED STATES PATENT OFFICE

MILDRED L. JAMES, OF BROOKLYN, NEW YORK

DESIGN FOR A DRESS

Application filed August 31, 1931. Serial No. 40,970. Term of patent 3½ years.

To all whom it may concern:

Be it known that I, MILDRED L. JAMES, a citizen of the United States, residing at Brooklyn, in the county of Kings and State of New York, have invented a new, original, and ornamental Design for Dresses, of which the following is a specification, reference being had to the accompanying drawing, forming a part thereof, wherein:

showing my new design, with one side of the skirt lifted;

Figure 2 is a front elevation of the dress with the back of the skirt lifted.

The appearance of the back of the dress is substantially the same as that of the front.

I claim:

The ornamental design for a dress as shown and described.

(MRS.) MILDRED L. JAMES.
